UNITED STATES PATENT OFFICE.

JEAN REUSE, OF ENGHIEIEN, BELGIUM, ASSIGNOR TO THE SOCIÉTÉ ANONYME D'EXPLOITATION DES BREVETS REUSE AUX ETATS-UNIS D'AMERIQUE, OF BRUSSELS, BELGIUM.

CIGAR-MAKING MACHINE.

SPECIFICATION forming part of Letters Patent No. 608,914, dated August 9, 1898.

Application filed July 24, 1897. Serial No. 645,822. (No model.)

To all whom it may concern:

Be it known that I, JEAN REUSE, a Belgian subject, residing at Enghien, Belgium, have invented new and useful Improvements in 5 Cigar-Making Machines, of which the following is a specification.

This invention relates to cigar-machines of the general character of the machines heretofore patented to me, No. 552,447, dated 10 December 31, 1895, and No. 554,606, dated February 11, 1896.

The object of the present invention is to improve the mechanism of cigar-machines of this class in various particulars. The manipulators or jaws are duplicated at opposite ends of the machine and are so manipulated that the separate sets operate to cover the cigar with wrappers, which are wound in reverse direction, so that the machine may not 20 only make two cigars simultaneously, but may wind said cigars in reverse spiral directions. The operating mechanism is further improved to center the completed cigar in the jaws with certainty until the proper delivery mechanism is brought into operation.

The present invention also embraces improvements in the trimming, gumming, delivery, and other mechanisms of the machine.

Figure 1 is a front elevation of part of the 30 machine, the remaining portion of which is shown in Fig. 1^a, except that one set of jaws or manipulators is omitted from the two figures. Either set of jaws or manipulators may, in fact, be readily removed from the 35 machine. Figs. 2 and 2^a are together a rear elevation of the machine, one set of jaws or manipulators being omitted. Figs. 3 and 3^a together form a plan or top view of the machine, one set of manipulators being omitted. 40 The delivery apparatus and the driving mechanism shown will readily indicate the position of the removed jaws. Fig. 4 is a vertical section of Fig. 2 through the middle of the framework. Fig. 5 is a detached cross-sectional view showing the manipulators of one group in the position they occupy at the time of the stopping of the machine prior to the delivery of the cigar from the manipulators and omitting some of the parts of the 45 machine. Fig. 6 is a similar view of the ma-

chine, showing the manipulators or jaws in open position. Fig. 7 is a detail elevation and partial section of a part of the operating-gear. Fig. 8 is a detail, partly in elevation and partly in section, showing one of the 55 cutters and its connections. Fig. 9 is a similar view showing parts in different position. Fig. 10 is a detail, partly in section and partly in elevation, showing cigar-delivery mechanism detached. Fig. 11 is a similar view 60 showing different position of the delivery mechanism; Fig. 12, a broken section showing guide-levers and connections.

The framework of the machine, as shown, is rectangular in form and is indicated by A. 65 This frame has suitable supports for the various operative parts of the machine, among the most important of which are the parallel plates or pieces B B, which pieces afford supports or bearings for nearly all the driving 70 shafts or spindles which extend lengthwise of the machine.

The pieces B B are spaced and held apart by the filler-pieces B' B², one of these fillers being at the front and the other at the rear 75 of cheeks B B. There is thus a chamber open at top and bottom between the cheeks B B, and the cheeks are pierced for the longitudinal passage of shafts and rods. The shaft F, which is the main driving-shaft, has bearings 80 near the end of the frame and in these cheek-pieces, and the gear C is held to this shaft F between the cheek-pieces, so as to rotate with the shaft F. Oscillating plates I I also have their centers of motion on shaft F and may 85 rock about such shaft. Gear D has a projecting hub, which rests in a suitable recess or bearing in the plates I, so that the rocking of plates I about the shaft F will still maintain the gear D in engagement with the gear C on 90 the shaft F. The plates I I are tied together by ties I' I², so as to form connected bearings.

The gear E has hubs, which rest in circular recesses or bearings in the cheek-pieces B B. Thus both gears D and E will be driven from 95 the gear C; but gear D may change its relative position to gear E.

Outside the cheek-pieces B B and pivoted near the top of such cheek-pieces are guide-levers 15 and 16. These guide-levers have 100

slots therein, and jaw-driving spindles 11 and 12 pass through the slots in said levers.

The spindles 11 and 12 extend lengthwise of the machine and are secured eccentrically 5 in the gears D and E. The rotation of gears D and E therefore causes these spindles 11 and 12 to travel each in an annular path, the spindles remaining parallel, but not necessarily at the same distance apart. As these 10 spindles pass through the slots in guide-levers 15 and 16 they cause such guide-levers to swing back and forth toward the front and rear of the machine, the pivots by which the levers are connected to cheeks B B forming 15 the fulcrum.

Spindles 9 and 10 pass through openings in the levers 15 and 16 and so swing back and forth with said levers.

The spindle 9 at each side of the levers and 20 cheek-pieces forms the fulcrum or support for one pair of jaws or manipulators 1 and 2. The spindle 10 forms a similar fulcrum for pairs of jaws 3 and 4. These pairs of jaws are formed with fingers spread somewhat 25 apart, and the fingers of jaws 1 and 2 lie between the fingers of jaws 3 and 4, and vice versa. The tails or lower extensions of these jaws are slotted, as indicated in Figs. 5 and 6 of the drawings.

30 The spindles 9 and 10 have a swinging movement imparted to them by the guide-levers 15 16, as has been explained. The spindles 11 and 12 extend through the slots in the tails of the jaws, as indicated. These slots 35 have such relation to the fingers of the jaws that the annular travel of each spindle 11 or 12 causes the fingers of the pairs of jaws through which said spindle passes to open and close alternately. As the jaws have both 40 an opening and closing and a rocking movement, the cigar-fillers or the fillers and wrappers in the jaws will be caused to rotate on their axes, as explained more fully in former patents hereinbefore referred to.

45 There is a tip-former 13 at the end of each set of manipulator-jaws. The arrangement of these tip-formers, as shown, at the ends of the jaws toward the partitions or cheeks B cause the cigars to be formed with their tips 50 pointing toward each other in the machine. The effect of this arrangement is to cause the manipulator-jaws to roll the cigar-fillers at opposite ends of the machine in opposite directions. Thus on the same machine cigars 55 may be made having the covering-leaf or wrapper rolled to the right and cigars having the covering-leaf or wrapper rolled to the left, and covering-leaves or wrappers may be cut out of the right-hand side of a tobacco-leaf for cigars made in one set of manipulators, and leaves or wrappers cut out of the left-hand side of the same or similar leaves 60 may be used in the other set of manipulators in the same machine and operating about simultaneously, as will be explained.

The ends of the spindles 9, 10, 11, and 12 being free, the sets of manipulators or jaws

may be slipped on these spindles from the ends. Each set of manipulators may be held against its tip-former by rings 7 and 7^x, attached to the shafts by set-screws, and by a coiled spring 6, interposed between one of said rings and one set of the jaws and acting to press the jaws toward the tip-former. The space between the fingers of one set of jaws 75 1 2 is a little more than the width of the fingers of the jaws 3 4, and these jaws 3 4 are pressed by spring 6 toward the tip-former.

The mechanism which successively effects the stoppage of the machine, the cutting off 80 of the thick end of the cigar, the simultaneous opening of the two pairs of manipulators of each group, and the removal of the finished cigars from the open jaws or manipulators is actuated by the crank-handle O. 85 This crank O is keyed to the end of a shaft P, which shaft P is supported in bearings at one end of the machine and extends crosswise thereof. A beveled pinion P' on shaft P engages beveled pinion N' on shaft N, 90 which shaft N is supported in bearings Q at the back of the machine and extends lengthwise thereof. This transverse arrangement of shaft P places the crank in convenient operative position and enables the operator to 95 observe the manipulators at all times.

A rod or bar R extends along the front of the machine and is supported by pins or screws R' R', passing through slots in bar R and into the frame, so that the bar R may be 100 moved lengthwise. Bar R terminates at each end in a fork. The fork R³ has its arms at opposite sides of a cam P², which is secured on shaft P. By turning the crank O the cam P² causes the bar R to slide endwise. The 105 rocking of shaft P is stopped by the flat face of cam P² engaging the shoulder R⁷ on the bar R when bar R has moved as far as slots R² permit. A reverse rotation of crank O moves the bar R in reverse direction.

The fork R⁴ on bar R has its arms at opposite sides of the lever R⁵, which lever is supported on a fulcrum or pivot in the frame. The movement of bar R to the right swings lever R⁵ so that a projection R⁶ comes in 115 front of a projection on the fly-wheel G and quickly stops the movement of said wheel and driving-shaft F and the parts driven by said shaft. A reverse movement of crank O, which brings the flat face of cam P² against 120 stop R⁷, shifts the bar R to the left, swings lever R⁵, and permits the shaft F to again rotate. Any suitable system of friction or clutch mechanism which permits shaft F to be driven or brought to a sudden stop by the 125 stop mechanism may be used with the machine.

The bevel-pinion P' on shaft P is connected to a collar P⁴, loose on said shaft P. Collar P⁴ is cut away for a part of its circumference, 130 so as to permit about a quarter-turn of the crank O and shaft P, (needed to stop shaft F,) while pinion P' remains stationary; but if the turning of crank-handle O be continued

a pin or stop P^5 on shaft P meets shoulder P^6 on collar P^4 (see Figs. 3^a and 7) and causes the pinion P' to turn, and with it pinion N' and shaft N .

5 Shaft N carries cams N^2 N^3 , each of which actuates one of the knives S , which knives S cut off the thick ends of the cigars in the jaws of the machine. The knives S are similar in construction and operation.

10 Each knife S is mounted on a curved lever S' . The levers S' are fulcrumed on shaft 25. A short arm of lever S' rests on a cushion or pad S^5 when the knife is raised to extreme position. A spring S^6 , connected to lever S' below the fulcrum and to the frame, tends to hold the knife up.

15 A push-bar or lever S^2 is pivoted to lever S' between its fulcrum and the knife. Lever S^2 has a projection S^3 , against which the tooth N^3 of cam N^2 bears when said cam is in its initial starting position.

20 A set-screw S^4 extends through the outer end of lever S^2 and can be projected more or less below said lever.

25 When cam N^2 rotates to press lever S^2 toward lever S' and thus depress knife S , as in Fig. 9, the set-screw S^4 will ultimately engage the curved surface of cam N^2 and so limit the engagement of the flat face of the

30 cam with the arm S^3 of the lever S^2 , and thus the knife movement may be regulated. As soon as cam N^3 passes out of engagement with arm S^3 the lever S^2 is released and spring S^6 operates to lift the knife suddenly. The ac-

35 tual movement of the knife can thus be predetermined and the cutting stopped at such distance as to just sever the cigar and avoid contact with the jaws.

40 The downward movement of the knife S carries the knife into a slot or recess near the outer end of the jaws and cuts off the large end of the cigar held in the jaws. As the jaws or manipulators are of various sizes, the movement of the knife with some jaws

45 must be greater than with others. The stoppage of the shaft F and the cutting off of the ends of the cigars are effected while jaws 3 and 4 are open and jaws 1 and 2 are closed on the cigar. Before the finished cigar

50 can be released these jaws 1 2 must be opened. Their opening is effected by mechanism about to be described.

The gear D , which actuates spindle 11, is mounted between plates I , as has been explained. The tie-rod I^2 , connecting plates I , is connected by a rod K to another rod L , which rod L is pivotally connected to a disk or cam lever M . Disk or cam lever M is loosely mounted on a sleeve N^4 , and sleeve N^4

60 is fast on shaft N . A spring L' , connected to rod L and to the frame, tends to move rod L toward the back part of the machine, thus tending to rock plates I about shaft F , and pressing on the arm of disk-lever M , tending

65 to rock said lever or cam about shaft N ; but the disk M has a notch M' on its rounded surface, into which notch the pawl M^2 is normally

pressed by a spring M^3 . Pawl M^2 is broader than disk M , and a cam N^5 on a sleeve N^4 is close alongside the disk M , and the rotation 70 of shaft N (after the operation of knives S S , as described) causes cam N^5 to lift pawl M^2 and free it from the notch or tooth M' , so that disk M may rock, and the plate I , rocking about shaft F , causes the wheel D and spindle 75 11 to descend. Spindle 11, moving in the slots in the tails of the manipulators 1 2, causes the opening of their jaws, as will be understood by reference to Figs. 4, 5, and 6. The different sets of manipulator-jaws being open, as above, 80 the cigars are raised by raising-levers T T , which levers have hooked arms that normally lie down in recesses between the teeth of the manipulator-jaws.

Levers or lifters T are keyed to a shaft T' , 85 extending lengthwise of the machine, having bearings in cheeks B B . A spring T^2 , coiled about the shaft and connected thereto at one end and to the frame at the other end, tends to rock the shaft T to position to hold the delivery-levers T in position to lie under the cigars in the jaws. A ring T^3 , keyed to shaft T near one of the cheeks B , has projections T^4 thereon, which projections limit the rocking movement of shaft T by engaging one or the other of stops T^6 or T^6 on the cheek B . A belt T^7 , secured to the hub T^8 of lever T , passes partly around this hub and is partly wound on and secured to a sleeve U , loosely mounted on shaft N . A spring U' , coiled on shaft 100 N between sleeve N^4 and the sleeve U , holds the latter against a sleeve V , keyed on shaft N .

The adjacent faces of sleeves U and V are cut to form a clutch, the engaging parts U^3 and V^4 of which clutch are brought into contact 105 when the rotation of the shaft N has caused the opening of the manipulator-jaws, as described. The rocking of shaft N with the clutch in engagement turns sleeve U , winds belt T^7 thereon, and thus rocks shaft T' 110 through the belt connection and against the resistance of its spring. This rocking of the shaft lifts the hooks of levers T to position shown in Fig. 11 and causes the cigars to roll along the extension of levers T into a receptacle. The extensions of levers T extend 115 nearly upright when the hooks of these levers lie under the cigars in the jaws and are guides along which the cigars roll when the hooks are raised.

120 On the periphery of sleeve U there is an oblique projection U^2 , and as the sleeve rotates to move levers T to delivery position this projection U^2 bears against a stud W , fixed to the base of the machine. This stud 125 acts to uncouple the clutch U V , and the action of spring T^2 restores the levers and connections to delivery position for a subsequent cigar.

130 The reversal of movement of crank-handle O restores all the parts of the machine to position for receiving new fillers. The fillers may then be entered and will be manipulated by the jaws in general, as explained in the

patents referred to. The wrappers will be fed by hand to the cigars in the jaws, due care being used to enter a right or left wrapper in the separate jaws, as the circumstances require.

The gum for pasting or gumming the cigar tip may be contained in the receptacle X above the central part of the machine and fixed to a covering-plate. Conduits X' lead from this receptacle to ducts Y on each side of the plates B B, and so in front of the tip-former. In each duct Y there is a piston Z. The rod of this piston has a head Z', which acts as a valve for closing the passage from conduit X'. A spring Z² keeps the valve against the opening from the conduit. A stud Z³ passes through a slot in plate W and connects to piston Z, and by this stud the piston may be moved to open valve Z'. Gum passes by gravity along the conduit X' into duct Y. When the piston is pressed forward, gum enters the chamber Y and passes into the opening in plate W' until flush with the surface of said plate. The attendant has only to control the feed of the gum to the groove and apply the tip of the wrapper to the gum before entering the wrapper in the jaws.

In operating this duplex machine the operator enters the filler into one of the sets of jaws, and while the jaws are compressing and rolling such filler the operator enters the filler into the other set of jaws. The wrappers, of suitable form and material, as has been explained, are then applied to the cigars, first to one and then to the other, and these are rolled on the cigar by the machine. At the proper time the crank-handle is turned to stop the manipulator mechanism, to cut off the large ends of the cigars, and to deliver the cigars from the machine.

As the tip-formers in the machine illustrated are near the center of the machine, the cigar-tips will both point toward the center of the machine. Then in rotating, while the direction of rotation of both cigars will be in the same direction, the spiral wind of the cigars will be in opposite directions—that is, one spiral will wind to the right, the other to the left.

50 I claim—

1. In a cigar-machine the driving means and set of manipulators having intermeshing fingers with spaces between the fingers of one jaw of a width greater than the width of the fingers of the other jaw resting in said spaces, and a spring bearing one of the jaws in the direction of the length of the other jaw, all combined substantially as described.

2. In a cigar-machine the driving means, a set of manipulators consisting of two pairs of jaws with intermeshing fingers of one pair resting in spaces between fingers of the other pair, said spaces being wider than said fingers, and a yielding presser bearing one pair of the jaws in the direction of the length of the other pair, all combined.

3. In a cigar-machine, a pair of manipula-

tor-jaws one jaw having fingers of less width than the spaces between fingers of the other jaw, a tip-former at each end of the pair of jaws, and a spring bearing one of the jaws toward the tip-former, all combined.

4. In a cigar-machine, a supporting-spindle and a driving-spindle and means for driving said spindles substantially as described so as to leave their ends free, a pair of manipulator-jaws adjustable to working position on said spindles, and a collar attachable to the supporting-spindle and sustaining a spring which bears on one of the manipulator-jaws, all combined.

5. In a cigar-machine the combination of manipulator-jaws and the rotating driving mechanism thereof, a rock-shaft operated by a handle and having a cam connected thereto, a slide-bar operated by said cam, and a lever mounted on the frame and shifted by the slide-bar into position to act as a brake to the rotating drive mechanism, substantially as described.

6. In a cigar-machine, the manipulator-jaws and the driving mechanism therefor, the brake to such driving mechanism controlled by a rock-shaft operated by a handle, the knife-driving shaft connected with said first-mentioned by a gear operating with a lost motion, and the swinging knife operated by the knife-shaft, all combined.

7. In a cigar-machine, the frame and supports, the driving-shaft and jaw-driving mechanism extending lengthwise of the frame, the crank-shaft extending transversely of the machine with its crank-handle at the front, and the knife and delivery mechanism connected to a shaft extending lengthwise at the rear of the machine and actuated by said crank-handle, all combined substantially as described.

8. In a cigar-machine, the manipulator-jaws and the driving mechanism therefor having a rotary driving-shaft and drive-wheel, a swing-lever pivoted on the frame with a brake projection in position to swing in the path of movement of the drive-wheel and stop the same, a slide-bar connected to said swing-lever, and a crank-shaft having a cam in a fork in said bar, and operating by its movement to shift said bar and so actuate the brake in either direction, all combined substantially as described.

9. In a cigar-machine, manipulator-jaws and the driving-gear therefor, a rock-shaft having an operating-crank and means connected thereto to operate as a brake on the driving-gear, a loose bevel-pinion on said rock-shaft and a projection on the shaft engaging the pinion to drive it after a partial rotation of the rock-shaft, and a knife-actuating shaft and connections driven from such bevel-pinion, all combined.

10. The knife mounted on a curved lever pivoted to the frame, a cushion on the frame against which the heel of the knife-lever rests normally, a spring connected to the knife-le-

- ver to hold it elevated, a push rod or lever pivoted to the knife-lever, and a hand-propelled cam acting on the said push-rod to depress the knife, all combined.
- 5 11. In a cigar-machine, the curved knife-lever and knife carried thereby, the lever-supporting spring and the cushion under the heel of the knife, the push-bar connected to said lever having a projection in position for 10 engagement with an operating-cam, and the set-screw in position to engage such cam and thus limit the action of said cam on the push-bar and knife-lever, all combined substantially as described.
- 15 12. In a cigar-machine, manipulator-jaws and means to drive and stop them, a cigar-cutting knife and actuating mechanism therefor driven by a hand-propelled shaft, and an adjustable connection between the knife-driver and the knife-support, whereby the 20 knife movement may be terminated at a predetermined distance, all combined substantially as described.
- 25 13. In a cigar-machine, two pairs of manipulator-jaws intermeshing as described, means for driving said jaws and for stopping the driving mechanism, and a hand-controlled mechanism by which one of the pairs of jaws can be opened when the driving mechanism 30 is stopped, all combined substantially as described.
- 35 14. In a cigar-machine, two pairs of manipulator-jaws with intermeshing fingers, driving-spindles for said jaws and means under control of the operator for stopping such driving-spindles, and a hand-controlled device by which one set of the driving-spindles may be opened when the power mechanism is at rest, all combined substantially as described.
- 40 15. In a cigar-machine, the manipulator-jaws and their driving and starting mechan- ism, the pivoted cheeks sustaining one of the driving-gears, and the driving-spindle operating on one pair of the jaws, the spring tending to rock said cheeks and thus open the jaws, 45 and the hand-controlled mechanism acting to release said cheeks and render the spring operative, all in combination.
16. In a cigar-machine, the manipulator-jaws and their driving-spindles, one of said spindles supported by pivoted cheek-pieces, a spring connected to said cheek-pieces to swing the same, a locking-pawl by which the cheek-pieces are held against movement, and a cam under control of the operator in position to release said pawl and permit the spring and connections to move the spindle and thus open a pair of jaws, all in combination substantially as described.
17. In a cigar-machine, the manipulator-jaws, the delivery-levers, a belt connected to said levers leading to a hub on a rock-shaft, and hand mechanism whereby the rock-shaft may be rocked to actuate the delivery-levers, all combined substantially as described.
18. In a cigar-machine, the manipulator-jaws, the delivery-levers, a spring acting to hold the levers in the jaws, a belt connected to the delivery-levers and to a hub on the hand-operated rock-shaft whereby the levers 70 are lifted, a clutch engaging said hub, and an automatic clutch-detaching device whereby the rock mechanism is released and the delivery-levers permitted to return under the influence of the spring, all the specified elements combined.

In witness whereof I have signed my name in presence of two witnesses.

JEAN REUSE.
